UNITED STATES PATENT OFFICE.

HENRY C. HERR, OF PITTSBURGH, PENNSYLVANIA, ASSIGNEE, BY MESNE ASSIGNMENTS, TO SOUTH SIDE TRUST COMPANY, TRUSTEE, OF PITTSBURGH, PENNSYLVANIA, A CORPORATION OF PENNSYLVANIA.

MACHINE FOR FORMING EXPANDED METAL.

1,195,222.

Specification of Letters Patent. Patented Aug. 22, 1916.

Application filed January 6, 1912. Serial No. 669,881.

To all whom it may concern:

Be it known that I, HENRY C. HERR, a citizen of the United States of America, residing at Pittsburgh, in the county of Allegheny and State of Pennsylvania, have invented certain new and useful Improvements in Machines for Forming Expanded Metal, of which the following is a specification, reference being had therein to the accompanying drawings.

The invention relates to machines for forming expanded metal and consists in various features of construction as herein-after set forth.

In the drawings.—Figure 1 is a side elevation of the machine; Fig. 2 is a plan view thereof; Fig. 3 is an end elevation; Fig. 4 is an enlarged elevation showing the engagement of the slitting rolls; Fig. 5 is an enlarged cross section of the rolls; Fig. 6 is an enlarged cross section showing the drawing rolls; Fig. 7 is a cross section showing the gripping jaws for expanding the sheet; Fig. 8 is a plan view thereof; Fig. 9 is a view similar to Fig. 7 showing the parts in different adjustment; Fig. 10 is a side elevation of Fig. 9; Fig. 11 is a side elevation of the cam controlling the gripping jaws; Fig. 12 is a plan view of the blank after the first slitting operation; Fig. 13 is a similar view of the blank after the second slitting operation.

The machine is particularly designed for the formation of expanding metal in which a portion of the blank remains unaltered in dimensions but is adjacent to and integral with an expanded portion of the sheet. This necessitates the drawing or elongation of the strands forming the expanded portion of the sheet to compensate for the natural contracting effect on the length of the sheet due to the lateral expansion thereof. In other words, in the usual process of expanding a stranded sheet the blank is contracted longitudinally as it is expanded laterally, but this would not permit of leaving any portion of the sheet unexpanded, for the obvious reason that such portion would be buckled or crimped by the longitudinal contraction of the sheet. Such an effect is overcome in my improved machine by the operation of means for elongating the strands and by the association of such means with the lateral expanding mechanism.

Another novel feature of my improved machine is the construction for forming the stranded sheet by successive slitting operations.

In detail, A is a suitable frame work upon the forward end of which is mounted the sheet stranding mechanism. This stranding mechanism comprises two pairs of slitting rolls B, B' and C, C' which successively operate upon the sheet as it is fed therebetween. The rolls B' and C' are provided with alternate rings and grooves and the rolls B and C are provided with corresponding rings and grooves, the rings being however, divided into segments D by interruptions D'. These segments D engage the grooves of 70 their corresponding rolls B and C and in the operation of passing a sheet metal blank therebetween, each segment will slit and depress a strand, while the interruptions D' will leave unslotted bonds. The spacing of 75 the rings and grooves is such as to produce by each pair of rolls, slits separated from each other by the width of strands, while the slits produced by the rolls C and C' are midway between the slits produced by the rolls 80 B and B', and the bonds produced by the respective pairs of rolls are likewise spaced longitudinally midway between each other. Thus after the sheet has passed the second pair of rolls it is properly stranded for expansion.

In addition to the intermeshing rings and grooves on the rolls B, B' and C, C', each of said rolls is provided with a portion in rolling contact with the corresponding portion 90 on the companion roll, the radius of such portion being less than that of the rings and more than that of the bottom of the grooves. As shown, E and E' are the peripheral contacting portions on each pair of rolls, these 95 being arranged at opposite ends and adapted to leave upon opposite sides of the sheet metal blank, marginal bands which are unslotted.

The expanding mechanism comprises 100 means for drawing the opposite edges of the sheet in opposite directions and associated means for elongating the strands so as to avoid any contraction in the length of the blank or any crimping stress on the unslotted marginal portions thereof. For 105 expanding or enlarging the sheet laterally, I preferably employ a series of gripping de-

5 vices which engage with the margins of the sheet and which travels forward therewith but in divergent planes. The specific construction is illustrated in Figs. 7 to 10 and 5 comprises a pair of chains F which travel longitudinally of the bed or frame A in divergent planes and are operated by suitable springs G. These chains are provided at suitable intervals with grippers H comprising 10 a laterally extending jaw member H' fixed to the chain, and a pivoted jaw member H² which in one position will grip with the jaw H' to engage the sheet. The jaw member H² is preferably also provided with 15 a pin H³ for perforating the marginal portion of the sheet and passing into engagement with a recess H⁴ in the jaw member H' thereby forming a pivotal engagement with the sheet. The pivotal jaws H² are 20 actuated by rolls I thereon which travel in engagement with a groove way J mounted upon a frame of the machine, while the chain F is guided by grooved rolls K and K' also engaging groove-ways in the member J. At the point where the stranded blank first comes into engagement with the chains J, the roll I is in engagement with the cam portion J' of the guide, which 25 swings the jaw H² into the position shown in Fig. 9. As soon however, as the blank is in engagement with the under jaw H' the jaw H² is swung downward by the cam J' until the pin H³ engages and perforates the sheet, as shown in Fig. 7. The divergent 30 movement of the chains will then draw the opposite jaws of the sheet outward and cause the lateral expansion.

35 The longitudinal elongation of the strands is preferably effected by successive operations occurring at intervals in the lateral expansion. As shown, a series of rolls L, L', etc., are arranged transversely across the machine above and below the stranded sheet and intermediate the unslotted marginal portions thereof. The length of these rolls 40 is progressively increased toward the rear end of the machine and the last rolls L' are of sufficient length to include the marginal bands as well as the stranded portion. The 45 slitting operation will cause a certain degree of elongation in the strands, and therefore, the sheet when first engaged by the jaws H' and H² will be expanded laterally to take up this elongation before reaching the first pair of rolls L. In passing between 50 these rolls the strands are further elongated, providing sufficient slack for the next expansion operation at the completion of which the second pair of rolls L' engages the strands and further elongates them. Thus the operation is repeated until the full 55 width of expansion is obtained, after which the entire sheet including the unexpanded margins, passes between the rolls L', pressing it into a single plane.

At the rear end of the frame the jaws H² are again released by the rolls I thereof engaging another cam portion J' of the track and the released sheet is fed out from the machine.

70 The rolls L, L', etc., are driven at the proper speed through suitable mechanism such as the spiral gears M which connect said rolls to a longitudinally extending drive shaft N and spiral gears O connecting the shaft N to the slitting rolls B and C'.

75 As has been stated the grippers H have a pivotal engagement with the sheet by reason of the pin H³ engaging a recess H⁴. This provides for adjustment necessary by the slight warping of the sheet in expansion and avoids danger of tearing.

80 What I claim as my invention is:

1. In a machine for expanding metal, the combination with means for progressively laterally expanding a stranded sheet, of means operating successively during the progressive expansion for elongating the strands of said sheet to compensate for angular movement thereof without contrac- 85 tion in length of the blank.

90 2. In a machine for expanding metal, the combination with means for stranding a sheet leaving portions thereof unstranded, of means for laterally expanding the stranded portion of the sheet during the longitudinal movement thereof, and means operating upon the strands during their longitudinal movement to elongate the same and compensate for the angular movement thereof.

95 3. In a machine for expanding metal, the combination with means for advancing a stranded sheet, of means operating during the advance of said sheet to laterally expand the same, and a series of drawing rolls successively operating upon the strands of the sheet prior to the completion of the expansion to elongate the same and compensate for their angular movement.

100 4. In a machine for expanding metal, the combination with means for advancing a stranded sheet, of means for laterally expanding said sheet in the same plane during the longitudinal advance, and a series of drawing rolls of progressively increasing 105 length operating upon the strands prior to the completion of the expansion to elongate the same and to compensate for the angular movement thereof.

110 5. In a machine for expanding metal, the combination of a pair of divergently moving carriers, a series of grippers on said carriers for successively engaging with the opposite margins of a stranded sheet to simultaneously longitudinally feed and laterally expand the same, and a series of drawing rolls successively operating upon the strands intermediate said grippers to elongate the same and compensate for the angular movement thereof.

6. In a machine for expanding metal, the combination of a pair of divergently moving carriers, a series of grippers on said carriers for successively engaging with the opposite margin of a stranded sheet to simultaneously longitudinally feed and laterally expand the same, each of said grippers comprising a pair of jaw members arranged upon opposite sides of the sheet, and a pin on one member for perforating the sheet and engaging a recess in the other member forming a pivotal engagement.

7. In a machine for expanding metal, the combination with divergently moving carriers, of a series of grippers upon said carriers each comprising a pair of jaws passing respectively below and above the sheet to be expanded, a pin upon one of said members for perforating the sheet and engaging a recess in the other member, and means for moving the pin member into and out of engagement with said sheet at the opposite ends of the carrier.

8. In a machine for expanding metal, the combination with means for successively engaging with the opposite margins of a stranded sheet to simultaneously longitudinally feed and laterally expand the same, of a series of drawing rolls successively operating upon the strands intermediate said margin engaging means prior to the completion of the expansion to elongate the same and compensate for the angular movement thereof.

9. In a machine for expanding metal, the combination with means for expanding a stranded portion of a sheet intermediate unstranded portions thereof, of means engaging the stranded portion of the sheet for equalizing the length of the stranded and unstranded portions thereof.

10. In a machine for expanding metal, the combination with means engaging the unstranded marginal portions of a stranded sheet for laterally expanding the stranded

portion and means successively operating upon the strands for elongating the same.

11. In a machine for expanding metal, the combination with means for laterally expanding a stranded sheet in the same plane, of means successively operating upon the strands of the sheet prior to the completion of the expansion to elongate the same and to compensate for the angular movement thereof.

12. In a machine for expanding metal, the combination with means for expanding a stranded portion of a sheet by a series of operations, of means for elongating the strands prior to the complete expansion thereof by a series of operations.

13. In a machine for expanding metal, the combination with means engaging the unstranded marginal portions of a stranded sheet for expanding the stranded portion by a series of operations, of means operating upon the strands previous to the completion of the expansion thereof for elongating the same by a series of operations.

14. In a machine for expanding metal, the combination with means for simultaneously laterally expanding and longitudinally feeding a stranded portion of a sheet, of successive means operating upon the strands of said sheet to elongate the same and to compensate for the angular movement thereof.

15. In a machine for expanding metal, the combination with means for progressively laterally expanding a stranded sheet, of positively rotated rolls operating successively during the progressive expansion for elongating the strands of said sheet to compensate for angular movement thereof without contraction in length of the blank.

In testimony whereof I affix my signature in presence of two witnesses.
